SPOT LAMP

George E. Gravenstine, Dayton, Ohio, assignor to
 The S. H. Thomson Manufacturing Company,
 Dayton, Ohio, a corporation of Ohio

Application February 19, 1942, Serial No. 431,543

3 Claims. (Cl. 240—61.13)

This invention relates to spotlamps and more particularly to spotlamps adapted to be carried on a vehicle and arranged so that the direction in which the beam of light travels can be readily controlled.

One object of the invention is the provision of a spotlamp including a lamp assemblage having parts providing for control of the light direction about a plurality of axes, such light assemblage being adapted to be very quickly attached to and detached from a carrying assemblage which is mounted on the vehicle and which includes control members so that the light beam may be directed or controlled from within the vehicle.

Another object of the invention is the provision of a spotlamp which is particularly adapted for use on a tank or other vehicle where it may be important to carry the lamp itself within the vehicle when it is not actually in use, the lamp construction embodying a lamp housing together with carrying and controlling parts constituting one assemblage which can be readily removed from and attached to another assemblage which is fixed to the wall of the vehicle and incorporates controllable parts for controlling the direction of the beam of light from within the vehicle.

Other objects and advantages of the invention will be apparent from the following description, the appended claims and the accompanying drawing.

In the drawing:

Fig. 1 is a side elevation, partly in section, and showing a lamp embodying the present invention;

Fig. 2 is a rear elevation of the removable lamp assemblage; and

Fig. 3 is a central vertical section showing the supporting part of the lamp structure.

Referring more particularly to the drawing, in which the same reference numerals have been used to designate like parts in the several views, the device, as shown, incorporates a spotlamp having provision for moving the lamp housing about a plurality of axes so that the direction of the beam can be readily controlled. The lamp housing is supported on a wall portion of a tank or other vehicle where it may be important to remove it, so it may be carried in a safe place within the vehicle when it is not needed for use. The construction is such that the lamp housing may be very quickly and easily attached in its operative position and connected to the operating controls which extend into the tank and which provide for control of the direction of the light beam, in use.

The lamp housing preferably includes a sheet metal body 11 which supports a reflector 12 and a suitable lens 13. The reflector carries a lamp socket 14 in which the light bulb 15 is mounted and a focusing device 16, operated by an adjusting screw 17 permits axial adjustment of the position of the lamp bulb so that the beams of light projected from the reflector will be properly focused.

10 The sheet metal body member is secured as by means of screws 19 to a recessed yoke member 20, preferably a metal casting, forming part of the lamp housing. This yoke member affords a recess 21 extending up into the housing. A rotatable mounting member 23, which also serves as a gear housing, extends up into this recess and is mounted for rotation about its own axis as will be described, and carries the lamp housing with it. With the axis of the mounting member 23 vertically arranged, as shown, the turning movements of this mounting member will cause horizontal swinging of the beam of light projected from the reflector. The upper end of the mounting member 23 is pinned or otherwise fixed to a 20 horizontally extending shaft 24 which projects out from the mounting member at its opposite ends. At one end it is journaled in the yoke member as shown at the left in Fig. 2, and at its other end it is rotatably journaled in a nut 24a which is threaded in the yoke member and fixed to the yoke member by means of a pin 24b. Carried by a reduced portion of shaft 24 at the right-hand side thereof in Fig. 2 is a beveled gear 25 operated by pinion 26 fixed on the upper end of a rod 27. 25 The gear 25 is free to rotate on the shaft 24, being held in place thereon by the shoulder formed by the reduced shaft portion, and is interlocked or fastened to the nut 24a so that when the gear 25 is rotated by the pinion 26, the yoke member is 30 turned. A nut 24c threaded on the end of the shaft 24 bears against a spring washer 24d so as to apply a yielding frictional restraint for the rotational movements of the yoke member with respect to the non-rotatable nut 24a and the 35 shaft 24. The nut 24c also serves to hold a shoulder portion of the shaft 24 against the side of the gear 25, the other side of the gear engaging, of course, against the nut 24a as will be apparent. It will thus be clear that as the rod 27 is turned, 40 the housing is adjusted about the longitudinal axis of the shaft 24, and as the mounting member is turned, it turns the housing member about an upright axis.

The rod 27 is rotatable within a sleeve 28 which 45 has external threads 29 at its upper portion, en-

gaging threads in the mounting member 23, and a set screw 30 holds these two parts in secured position with respect to one another. By turning the sleeve 28, the lamp housing is rotated about its vertical axis.

The lamp bulb is supplied with electric current through a connection 32 which extends out from the lamp housing and which is provided with a connection plug 33 by means of which it may be readily connected to a suitable current supply socket.

The parts described provide a lamp assemblage together with operated members, which may be readily connected to and detached from a support which is arranged permanently in position on the tank or vehicle. This support, which has been shown in Fig. 3, is arranged on the wall portion 34 of the vehicle, this wall portion, as shown, being a substantially horizontally extending plate of armor which is at a convenient location in front of the operator of the tank so that the controls or operating members for the lamp housing, which extend into the tank, can be readily moved by the operator, who may remain in a protected position in the tank and pick out the target, at night, so that he may be enabled to effectively direct the guns of the tank towards the target.

Secured, preferably by welding, to the inner side of the wall portion 34 is a lower bearing member 35, and an upper bearing member 36 is similarly secured to the outer surface of the wall portion, these two bearing members having axial passages aligned with a hole or passage 37, of rather small diameter, extending through the wall portion. The upper bearing member 36 is provided with bearing surfaces 38 and 39 cooperating with corresponding bearing surfaces provided on the lower end of mounting member 23, and providing for rotational movements of the mounting member 23 about its own axis, when positioned on the bearing member in the manner shown in Fig. 1. In this position, the mounting member 23 is held against upward movement with respect to the bearing member, by means of a latch 40 pivotally carried on a pivot pin 41 which is arranged in a boss on the mounting member. The latch 40 has a latching projection 40a which engages under the flange 40b of the bearing member. The latch 40 operates between a pair of stop arms 40c and 40d which are fixed parts of the mounting member 23. The stop arm 40d limits upward travel of the latch 40. This upward movement of the latch, however, can take place so as to free the latching projection 40a from under the flange 40b, by manual movement of the latch against the action of a spring 41a which engages at one end against the arm 40d and at the other end against a recessed portion of the latch 40. The spring therefore serves to yieldingly hold the latch in its down or latching position, and the weight of the latch itself is also effective to do the same. The latch can be instantly operated however to permit upward withdrawal of the mounting member 23 when it is desired to take off the detachable assemblage so that it may be carried in a safe place within the vehicle.

The lower ends of the rod 27 and of the sleeve 28 are notched or slotted axially so they may interengage respectively with lower rod and sleeve members 44 and 45, which have complementary notches or slots at their upper ends as indicated at 46. The rod 27 is thus clutched to the rod section 44 when the lamp housing is placed on

the upper bearing member, and the sleeve 28 is clutched to the sleeve section 45 when the lamp housing is placed in position, the connection between the rod portions and between the sleeve portions being effected as an incident to the mounting of the upper removable portion of the device. The connection between the rod portions and the connection between the sleeve portions is below the top of the bearing member 36 so that the rod section 44 and sleeve section 45 are protected within the bearing member when the detachable lamp assemblage is removed.

The sleeve section is secured by means of a set screw 43 to a rotatable collar 49 which is adapted for rotation in a socket 50 provided in the lower bearing member 35, thus fixing the sleeve section 45 against axial movement but permitting its rotation under the control of the operator. The lower end of the sleeve projects downwardly from the lower end of the bearing member and carries a hand knob 51, which is fixed to the sleeve by means of a suitable set screw 52. The lower end of the sleeve has an inwardly extending annular rib 53 which engages a shoulder 54 on the rod section 44, thus holding the rod section against downward movement while permitting its free rotation inside the sleeve. The lower end of the rod section 44 projects down beyond the end of the sleeve, and is secured by means of a set screw 55 to a hand knob 56. The two hand knobs, which are of generally hemispherical form and arranged close to one another, may be controlled one at a time or simultaneously, by the hand of the operator, to rotate either the sleeve or the rod or both.

A frictional restraint is imposed on the rotation of the sleeve section 45 so that under ordinary conditions of use, the mounting member 23 will be yieldingly held in any position to which it is adjusted. For this purpose, the lower end of the lower bearing member 35 is provided with several longitudinally extending slots 58 affording some contraction and expansion movements of the lower end portions of this bearing member. The bearing member at its lower end, also has a tapering form and is provided with screw threads 59 which are engaged by an adjusting nut 60. By turning the adjusting nut 60 in one direction or the other, the lower end of the bearing member is contracted or expanded to apply the correct amount of frictional restraint so that the direction in a horizontal plane in which the beam is directed will be maintained except as the operator changes this direction by turning the knob 51. A set screw 61 holds the nut 60 in any position of adjustment.

The diameter of the hole 37 which extends through the armor plate or other wall portion on which the lamp may be mounted, may be comparatively small as it is only enough greater in diameter than the sleeve section 45 to allow suitable clearance, so as not to destroy the strength of the wall structure.

The plug 33 through which an electric current is supplied to the lamp bulb is adapted for connection to a socket 63 into which the plug may be inserted. The socket 63 is fixed at a suitable location near the bearing member on the outer surface of the wall structure 34, and is connected by means of a cable 64 which passes through a hole 65, in the wall portion, to a suitable control switch 66 arranged within the vehicle where it may be conveniently operated. As will be apparent, the plug 33 can be instantly removed from the socket 63 when the detachable

lamp assembly is removed from its supporting means.

The lamp housing 11 may also have a handle 68 fixed directly thereon so that the direction of the light beam can be controlled by the operator who may reach out from the tank and move the lamp housing directly.

When the detachable lamp assemblage is removed the upper end of the bearing member 35 is closed by means of a suitable plug 69 which is held to the bearing member by a chain 70. The plug has a threaded portion 71 engageable with the threads 72 on the bearing member. When in position the top bearing surface of the bearing member is covered and the parts below the top of the bearing member are protected from dust, sand, etc.

While the form of apparatus herein described constitutes a preferred embodiment of the invention, it is to be understood that the invention is not limited to this precise form of apparatus, and that changes may be made therein without departing from the scope of the invention which is defined in the appended claims.

What is claimed is:

1. A device of the character described comprising outer and inner bearing parts adapted to be secured respectively to the outer and inner surfaces of a vehicle wall, a substantially vertically extending sleeve rotatably carried by said bearing parts, a rod rotatable in said sleeve, the outer ends of said rod and sleeve terminating within said outer bearing part, closely adjacent handles attached respectively to the rod and the sleeve for operating them independently from within the vehicle, a lamp housing, a mounting member pivotally supporting said housing for movement about a substantially horizontal axis, said mounting member being normally rotatably carried by said outer bearing part for movement about a substantially vertical axis, mechanism in said mounting member for pivotally moving the housing on said mounting member and having an interfitting clutch connection to said rod, means connected to said mounting member and having an interlocking clutch connection with said sleeve, a manually operable latch means for normally retaining said mounting member in operative relation upon said outer bearing part and manually releasable to provide for complete separation thereof, and detachable means for supplying electric current to said lamp housing, the lamp housing together with mounting member being instantaneously detachable and removable from the bearing parts and the rod and sleeve.

2. In a vehicle having a housing wall portion provided with an opening, outer and inner bearing parts secured to the outer and inner surfaces

respectively of the wall portion, a sleeve rotatably carried by the bearing parts, a rod rotatable in the sleeve, said rod and said sleeve projecting inwardly beyond the inner bearing part and terminating within the outer bearing part to be protected thereby, individual control members for operating the rod and the sleeve from within the vehicle, a lamp housing, a rotatable mounting member on which the housing is pivotally supported, mechanism in said mounting member for pivotally moving the housing with respect to the mounting member, a readily attachable and detachable clutch connection between the mounting member and the sleeve, a readily attachable and detachable clutch connection between said mechanism and said rod, and manually releasable latch means for normally retaining said mounting member in operative relation upon said bearing part and providing manual release for complete separation of said parts.

3. In a vehicle having a thick metal substantially horizontal wall portion provided with a substantially vertical passage, upper and lower bearing parts fixed to the wall portion at the outer and inner surfaces respectively of the wall portion, a sleeve rotatably carried by the bearing parts, a rod rotatable in the sleeve, individual control members for operating the rod and the sleeve from within the vehicle, a lamp housing, a rotatable mounting member on which the housing is pivotally supported for movement about a substantially horizontal axis, mechanism in said mounting member for pivotally moving the housing on the mounting member, said lamp housing mounting member and mechanism constituting a lamp assemblage which is readily attachable and detachable with respect to the bearing parts, the sleeve and the rod, a readily attachable and detachable clutch connection between the mounting member and the sleeve, a readily attachable and detachable clutch connection between said mechanism and said rod, manually releasable latch means carried by said mounting member and engageable with said upper bearing part to retain said parts in assembled relation while providing for complete separation thereof when manually released, an electrical supply socket carried by said wall portion and accessible from the outer side thereof, a connection plug detachably connected to said socket, an electrical connection from said plug to the lamp housing, and a closure member having a connection to said upper bearing part and operable to cover the top of the upper bearing part when the lamp assemblage is removed.

GEORGE E. GRAVENSTINE.
